(57) **CLAIM**

The ornamental design for an accessory for diving equipment, as shown and described.

DESCRIPTION

FIG. 1 is a perspective view of an accessory for diving equipment, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines where present depict portions of the accessory for diving equipment that form no part of the claimed design.
